Primary Examiner — Darlington Ly*Assistant Examiner* — Suzanne E Tisdell(74) Attorney, Agent, or Firm — Buchanan Ingersoll & Rooney PC(57) CLAIM

The ornamental design for a motor vehicle, toy and/or replica as shown and described.

DESCRIPTION

FIG. 1 is a perspective view of a motor vehicle, toy and/or replica showing my new design;

FIG. 2 is a front view thereof;

FIG. 3 is a rear view thereof;

FIG. 4 is a left view thereof;

FIG. 5 is a right view thereof; and,

FIG. 6 is a top view thereof.

The broken lines illustrate portions of the motor vehicle, toy and/or replica that form no part of the claimed design.
